UNITED STATES PATENT OFFICE

101,244

DESIGN FOR A FISH LURE

Takeo Y. Sato, Cambridge, Mass.

Application July 30, 1936, Serial No. 64,128

Term of patent 14 years

To all whom it may concern:

Be it known that I, Takeo Y. Sato, a citizen of the United States of America and resident of Cambridge, in the county of Middlesex, and Commonwealth of Massachusetts, have invented a new, original, and ornamental Design for Fish Lures, of which the following is a specification, reference being had to the accompanying drawing, forming part thereof.

In said drawing,

Fig. 1 is a plan view of a fish lure, showing my new design;

Fig. 2 is a fragmentary bottom view thereof;

Fig. 3 is a fragmentary side view; and

Fig. 4 is an end view of the head portion only of the design shown in Fig. 1.

The shaded portions of the head shown in Figs. 1, 2 and 3 indicate glass.

The dominant feature of my design resides in the appearance of the head of the fish lure shown in the drawing, and particularly to the arc-shaped wings which project laterally from the sides of said head, as best shown in Figs. 1, 2 and 4.

I claim:

The ornamental design for a fish lure substantially as shown and described.

Signed by me at Boston, in the county of Suffolk and Commonwealth of Massachusetts, this 29th day of July, 1936.

TAKEO Y. SATO.
